EGG BEATER

Filed May 2, 1932

By Lucy, Lacey,

Attorneys

UNITED STATES PATENT OFFICE

MATTHEW M. L. BURRELL, OF MILHEIM, PENNSYLVANIA

EGG BEATER

Application filed May 2, 1932. Serial No. 608,799.

This invention relates to egg beaters and has for an object to produce a beater so constructed that eggs and other materials may be beaten in small, deep containers, such as tumblers or cups without leaving unbeaten portions of the substance.

A further object is to provide a beater that will be highly efficient, quick in action, noiseless in operation, may be easily cleaned, may be manufactured at a low cost, and will be formed of a few simple, strong, rugged and durable parts that will not easily get out of order.

With the above and other objects in view the invention consists in certain novel details of construction and combinations of parts hereinafter fully described and claimed it being understood that various modifications may be resorted to within the scope of the appended claims without departing from the spirit or sacrificing any of the advantages of the invention.

In the accompanying drawing forming part of this specification.

Figure 1 is a side elevation with parts in section showing one form of the beater.

Figure 2 is a cross section taken on the line 2—2 of Figure 1 showing the chain agitator in plan.

Figure 3 is an enlarged detail cross section showing the method of securing the slide to the spiral shaft.

Figure 4 is a fragmentary side elevation showing a modified form of the shaft.

Figure 5 is a fragmentary section showing a modified form of slide and shaft, and

Figure 6 is a cross section taken on the line 6—6 of Figure 5 showing the method of securing the slide to the shaft.

Referring now to the drawing in which like characters of reference designate similar parts in the various views, 10 designates a grip or handle which may be formed of any desired hard substance, which is counterbored to provide an axial recess 11 which terminates at the inner end in a conical seat 12. The handle is provided with a ferrule 13 which may be secured in place in any preferred manner.

As shown in Figure 1, the spiral shaft 14

is formed of a pair of wires twisted together longitudinally. However, the shaft may be formed, as shown in Figure 4, by twisting a ribbon 15 spirally. Again the shaft may be formed by cutting a spiral groove 16 in a 55 rod 17, as shown in Figure 5. Regardless of the exact method of forming the shaft it is desirable that the shaft pass rotatably through the ferrule 13 of the handle and terminate in a conical bearing 18 which fits 60 in the seat 12. A ring 19 is fixedly secured to the shaft at such a distance from the bearing as to engage the ferrule 13 and prevent escape of the shaft from the handle.

The slide 20, shown in Figure 1, is formed 65 of a spiral length of wire or other suitable material and is shaped so that the opposite ends flare outwardly while the central portion is constricted. The ends 21 of the spiral are turned inwardly against the terminal 70 convolutions thereof. By referring particularly to Figure 3, it will be seen that the central convolution 22 of the spiral is flattened to substantially oblong shape and snugly encircles the spiral shaft 14. The straight sides 75 of this central convolution by fitting close against the surface of the spiral shaft function to rotate the shaft when the spiral slide is raised or lowered.

A stop ring 23 is fixed to the spiral shaft 80 below the slide and limits movement of the slide downwardly while the ferrule 13 limits movement of the slide upwardly.

The agitator comprises a disk 24 which is fixed to the lower end of the spiral shaft in 85 any preferred manner, such as by soldering or otherwise, and is provided centrally with a substantially oblong opening 25, as best shown in Figure 2, to permit the shaft to project through the disk and extend for substantially a half-inch, more or less, below the disk, as best shown in Figure 1. The disk is provided with an annular series of openings 26 which receive the inner links of short chains 27 and any desired number of these 90 chains may be employed.

The device is operated by placing the bottom of the shaft 14 and agitator into the container of the substance to be beaten. The bottom of the shaft must rest with moderate 100

pressure on the bottom of the container so that pivoting action may take place. The operator grasps the handle 10 with one hand. The slide 20 is grasped by the thumb and 5 forefinger of the other hand and oscillated up and down the spiral shaft 14. This causes the shaft to rotate rapidly, first in one direction, and then in the opposite direction. The disk 24 and chains 27 are also rotated with 10 the shaft. This rotation of the chains, first in one direction, then in the opposite direction, produces a rapid and forceful whipping effect and in turn produces the desired result effectively and in a very short period of time. 15 A modified form of a slide is shown in Figure 5, and comprises a spool 28 of any desired hard substance which is provided at one end of its bore 29 with a flanged bushing 30 which loosely receives the above described spirally 20 grooved steel shaft 17. A disk 31 is disposed over the opposite end of the bore and is provided with prongs 32 which are embedded in the end of the spool. The disk is provided centrally with a substantially square opening 25 33, as best shown in Figure 6, which conforms to the contour of the shaft. By virtue of the wall of the opening 33 hugging closely the grooved surface of the shaft, when the spool is raised and lowered, it rotates the shaft alternately in opposite directions. In this embodiment of the invention the shaft is equipped with a stop sleeve 34 which limits downward movement of the spool of the 30 slide. 35 In Figure 4 a modified form of bearing for the lower end of the shaft is shown to comprise a cup 35 which is provided with a slit 36 to receive the lower end of the spiral ribbon 15 and preferably the end of the cup is 40 conical, as shown at 37. The cup is provided with a flange 38 which is formed near the

edge with perforations 39 to receive the inner links of chains 40.

The handle 10 is common to all of the forms of the invention.

From the above description it is thought 70 that the construction and operation of my invention will be understood without further explanation.

What is claimed is:

1. An egg beater comprising a spiral shaft, 75 a handle rotatably receiving one end of the shaft, an agitator on the opposite end of the shaft, and a slide for rotating the shaft comprising a helical length of wire having a convolution intermediate the ends thereof flattened 80 to provide an oblong loop adapted to snugly conform to the contour of the shaft.

2. An egg beater comprising a spiral shaft, a handle rotatably receiving one end of the shaft, a slide movable longitudinally on the 85 shaft and having a portion snugly hugging the surface of the shaft to cause rotation of the shaft, a cup shaped bearing enclosing the lower end of the shaft provided at its upper end with a flange spaced above the lower end 90 of the shaft, and link chains carried by said flange.

3. An egg beater comprising a spiral shaft, a handle rotatably receiving one end of the shaft, an agitator on the opposite end of the 95 shaft, and a slide for rotating the shaft comprising a helical length of wire having a convolution substantially midway between the ends of the slide flattened to provide an oblong loop snugly conforming to the contour 100 of the shaft, the loops of the slide at opposite sides of said flattened loop being of graduated enlarged diameter whereby the slide is flared towards opposite ends thereof.
